COAT HANGER

Walter C. Helms, Jr., 3702 Acosta Road, Fairfax, Va.

Filed Oct. 27, 1964, Ser. No. 82,332

Term of patent 14 years

(Cl. D80—8)

FIG. 1.

FIG. 2.

FIG. 3.

FIG. 4.

FIG. 1 is a front elevational view of a coat hanger embodying my new design;

FIG. 2 is a rear elevational view thereof;

FIG. 3 is an elevational view taken from one end thereof;

FIG. 4 is an elevational view taken from the end opposite to that shown in FIG. 3.

I claim:

The ornamental design for a coat hanger, as shown.
